CONVEYER CHAIN FOR CAN FEEDING
MECHANISMS

Thomas B. Keesling, Campbell, Calif., assignor
to Food Machinery and Chemical Corporation,
San Jose, Calif., a corporation of Delaware

Original application February 25, 1946, Serial No.
650,017. Divided and this application October
18, 1948, Serial No. 55,052

1 Claim. (Cl. 198—28)

1 This invention relates to feed mechanisms and more particularly to a chain conveyor for elevating cylindrical objects, such as cans or the like, to the rotary valve of a cooker.

This invention is a division of my copending application Ser. No. 650,017, filed February 25, 1946, and now Patent No. 2,592,909 on a Feed Mechanism.

It is one object of the present invention to provide an elevator mechanism for feeding containers to a continuous cooker at a maximum speed with a minimum of shock to the containers.

Another object is to provide an elevator mechanism for rolling cylindrical containers along a confined path with a minimum of sliding or scraping so that the containers will not become marked or scratched.

Another object is to provide a conveyor mechanism for camming the containers from a feed elevator into a rotary receiver while permitting continuous rolling motion of the containers relative to the conveyor.

Another object is to provide a conveyor chain for an elevator mechanism for rolling cylindrical containers along a confined passage and for permitting deflection of the container out of such passage into a substantially vertical path merging into the arcuate path of a rotary receiver.

Other objects and advantages of the present invention will appear more fully from the following description in connection with the drawings in which:

Fig. 1 is a longitudinal section through an elevating mechanism embodying the present invention.

Fig. 2 is a section of a portion of Fig. 1 taken along line 2—2 thereof.

Fig. 3 is a section of a portion of Fig. 1 taken along line 3—3 thereof.

Fig. 4 is a section through the conveyor track taken along line 4—4 in Fig. 1.

The present invention has been illustrated in connection with a container feed mechanism for a continuous pressure cooker. Such container feed mechanism, in general, comprises a feed chute 1, an elevator 2, and a feed valve 3 associated with the pressure cooker 4.

The pressure cooker 4, which has been partially illustrated herein, may be of any conventional construction such as, for instance, shown in U. S. Letters Patent No. Re. 15,334, dated April 11, 1922, to A. R. Thompson.

Continuous cookers of this type comprise a cylindrical shell 10 closed at its ends to provide

2

a pressure treating chamber 12 and having an inlet opening 15 for admitting containers, presented thereto by the feed valve 3, into the chamber 12. A T shaped track 16 is secured to the inner wall of the shell and extends helically therealong from the inlet to the discharge end thereof. The containers are advanced along the track 16 by a rotary reel 17 comprising a plurality of spider wheels 18 suitably secured to a drive shaft (not shown) journaled for rotation coaxially of the shell in a manner well known in the art. The spider wheels carry a plurality of pusher bars 20 on their periphery and longitudinally of the shell so as to form a series of pockets 21 for supporting containers along the track 16.

Secured to the shell 10 adjacent the inlet opening 15 by means of rivets 26 is a casting 25 to which the housing 27 of the rotary feed valve 3 is secured by bolts 28. The periphery of the housing 27 has a valve outlet opening 30 adjacent to and communicating with the inlet opening 15 of the treating chamber 12 and also has a valve inlet opening 31 spaced therefrom exteriorly of the chamber. The housing 27 is provided with pressure tight bearings (not shown) at its sides and rotatably mounted within the same is a shaft 35 disposed parallel to the drive shaft for the rotary reel 17. Within the housing 27 and keyed to the shaft 35 for rotation therewith is a rotary turret 36 having a plurality of peripheral pockets 37 sealed with respect to each other. Each pocket is adapted to receive an individual container for transferring the same from the valve inlet 31 to the valve outlet 30.

The shaft 35 extends beyond one end of the housing 27 and is drivingly connected to the drive shaft for the reel 17 in the manner as taught in the aforesaid Thompson patent, Re. 15,334, so that the turret 36 is driven in synchronism with the reel 17. As seen in Fig. 1, the reel 17 is rotated counterclockwise and the turret 36 clockwise whereby the reel pockets 21 are caused to register with the turret pockets 37 as they pass the communicating inlet and outlet openings 15 and 30 of the chamber and feed valve, respectively. The lower margin 38 of the valve inlet opening 31 is located horizontally opposite the axis of the turret. The upper margin 39 of the opening 31 is spaced peripherally from the lower margin 38 so as to permit containers to enter the feed valve from above, that is, along a path which is substantially vertically tangent to the path the containers will travel while in the turret pockets 37.

The elevator 2 comprises a housing 45 having its lower end supported by a pedestal 46 and its upper end formed as a head casting 47 supported by the housing 27 of the rotary feed valve 3. The elevator housing 45 is provided with a trough-like closure 48 intermediate the pedestal and head casting which forms a guard for moving parts of the elevator as will later become apparent.

The head casting 47 is formed by two circular shaped side plates 51 and 52, each having downwardly extending sections 53 and 54, respectively. Adjacent the upper margin of the inlet opening 31 each side of the valve housing 27 is provided with a boss 55, adjacent the plate 51, Fig. 1, and 56 adjacent the plate 52, Fig. 3. A flange 57 extends horizontally from the respective side plates 51 and rests upon the boss 55 and a similar flange 58 on the plate 52 rests on the boss 56. Each adjacent side of the valve housing 27 at the lower margin of the inlet opening 31 is likewise provided with bosses 59 and 60. The flanges 57 and 58 of the side plates 51 and 52 are secured by bolts 63, Fig. 3, to the respective bosses 55 and 56 and the lower ends of the plates 51 and 52 are similarly secured to the bosses 59 and 60 adjacent the lower margin of the inlet opening 31. In this manner, the plates 51 and 52 are disposed with their inner faces flush with the end walls of the turret pockets 37 so as to permit passage of containers lengthwise therebetween.

The pedestal 46 comprises a substantially U-shaped casting 70 having a downwardly extending sleeve 71 which fits over a standard 72 having a foot portion 73. Bolted, as shown at 74, Fig. 1, 35 to the sides of the casting 70 are a pair of side plates 75 each having a guide slot 77 formed therein. Arranged in these slots for sliding movement therealong are floating bearings formed as a part of a yoke 80, later to be more fully described. A shaft 85 is supported for rotation in the floating bearings of yoke 80 and has a sprocket 86 secured thereto by set screws.

The circular side plates 51 and 52 are each provided with a laterally projecting bearing (not shown) and an elevator drive shaft 92 is supported in these bearings for rotation about an axis parallel to the shaft 35. A drive sprocket 93 is keyed to the shaft 92 for rotation therewith between the side plates 51-52 and one end of the shaft 92 extends beyond the head casting for driving connection in a conventional manner to the shaft 35.

Trained around the sprockets 93 and 86 is an endless elevator chain 100. The lower reach of chain 100 extends substantially parallel to a chord line struck across the periphery of the housing 27 from upper to lower margins 39 and 38, respectively, of the inlet opening 31. As best seen in Fig. 1, the lower reach of the chain 100 is spaced from the inlet opening 31 to permit the passage of containers between the chain and turret housing 27. The upper reach of the elevator chain 100 is also inclined and is supported parallel to an elevator track 105, as shown in Figs. 1 and 4. The elevator track 105 comprises two angle irons 106 and 107 spaced from each other by U straps 108. The straps 108 are welded to the lower faces of inwardly extending flanges 109 and 110 of the angle irons and have a chain supporting channel 111 welded to their recessed portion.

The trough-like closure 48, mentioned above, has its open upper edges secured by bolts 115 to the outer faces of vertical flanges 117 and 118 of the angle irons 106 and 107, respectively. The

upper end of the closure 48 fits between the side plates 51-52 and each side of the closure, as well as the upper ends of the angles 106 and 107, is secured to the respective side plates 51 and 52 by machine bolts 120. The lower end of the closure 48 fits between the side plates 75 which are secured to the casting 70 of the pedestal 46. Each side of the closure 48, as well as the lower ends of the angles 106 and 107, is secured to the respective side plates 75 by machine bolts 121. The elevator track 105 is thereby fixed between the pedestal and head casting and the closure 48 provides a chain guard therebetween.

The present invention is embodied in the single endless chain 100, the spacers between the respective links of which are rollers 124 adapted to ride upon the channel 111 as they travel along the same. Every third link of the chain 100 is provided with a flight 125 comprising outwardly extending brackets 126 and 127, each flared laterally with respect to the center of the chain. A pin 128 extends between the upper ends of each pair of brackets 126 and 127 and supports a roller 130 adapted to engage a container for pushing the latter upwardly and over the drive sprocket 93.

The containers are fed onto the upper reach of the elevator chain 100 by the gravity chute 1, hereinbefore mentioned, as seen in Fig. 1. The gravity chute 1 has a lower wall 135 terminating adjacent the elevator chain and also has side walls 136 secured to the sides of the closure 48 to support the discharge end of the gravity chute adjacent the elevator chain.

The containers gravitate along chute 1 in a steady stream toward the elevator and fall one after another into successive pockets 140 formed between the pusher rollers 130 of the chain 100. The containers fall into the respective pockets 140 and are supported on the inwardly extending flanges 109 and 110 of the elevator track 105. The upper reach of the chain is disposed at such an angle as to assure that each container will be supported in its respective pocket 140 as the containers are elevated.

The pusher rollers 130 are so disposed relative to the longitudinal axes of the respective containers engaged thereby that the periphery of each roller engages the periphery of a container, i. e., the rollers have single line contact with the respective containers. Therefore, while the containers are pushed up the inclined track 105 they are free to roll upon the inwardly extending flanges 109 and 110 thereof and also are free to rotate with respect to the pusher rollers 130. Accordingly, scraping of the containers along the track 105 and against the pusher rollers 130 is minimized and the containers are elevated with the least possible resistance to the drive mechanism for the chain 100.

The circular sections 51 and 52 of the head casting 47 are provided with inwardly extending flanges 141 and 142, respectively, which are tangent with respect to the flanges 109 and 110 of the track 105 to form a continuation thereof. The circular sections 51 and 52 are also provided, adjacent their peripheries, with inwardly extending flanges 143 and the spaces between the flanges 141 and 143 provide a track 145 around the sprocket 93. Therefore, as the containers leave the upper end of the track 105 they pass into the track 145 and are maintained within their respective pockets 140 as the chain 100 travels around the sprocket 93.

As the chain 100 begins its descending reach, the pockets 140 are inverted so that the containers will normally gravitate toward the feed valve 3. The valve housing 27 is provided with inclined surfaces 148 above the upper margin 39 of the inlet 31. These surfaces 148 are tangent to the ends of the flanges 143 at the periphery of the circular sections 51-52 and are parallel to the normal pitch line of the descending reach of the chain 100. Consequently, the containers are maintained within the pockets 140 until they pass the upper margin 39 of the inlet 31 and thereafter are free to gravitate toward the turret pockets 37 as the chain moves past the inlet 31.

The present apparatus is adapted to be operated at a high speed in which case the containers conveyed over the drive sprocket 93 are substantially pushed in a steady stream by the respective pusher rollers 130. While the containers are thus pushed, they are guided by the arcuate track 145 and subsequently descend toward the inlet opening 31 of the valve housing. In order to assure that containers fed at such speed will transfer from the chain pockets 140 to the turret pockets 37 a stripper guide 150 is provided.

The stripper guide 150 comprises a pair of stripper rails 151 and 152 (Fig. 2) spaced apart and in alignment with the respective inside flanges 141 and 142 on the inner faces of the side plates 51. The rails 151-152 are formed as an integral part of a casting 155 and each of them is reinforced by a triangular shaped web 156 extending rearwardly from the rails. The webs 156 are joined by a web 159 extending normal to the chain 100 and rearwardly therefrom to the apex of the triangular webs where the latter are joined by a transverse portion 160.

The casting 155 is mounted between the side plates 51-52 and is suitably secured in place opposite the inlet 31 by bolts (not shown). The upper end of each rail 151-152 abuts against the lower end of the inside flanges 141-142 and the descending reach of the chain 100 passes between the rails 151-152, as best seen in Fig. 2. The rails 151-152 are curved to guide the containers out of the chain pockets 140 and into a substantially vertical path which is tangent to the path the containers will travel while in the turret 36. The lower ends of the stripper rails 151-152 terminate adjacent the lower margin 38 of the inlet 31.

It may sometimes happen that containers rebound from the outside flanges 143 toward the chain pockets as the containers approach the inlet opening 31. Consequently, without the stripper guide 150, such containers would be carried beyond the desired path and might become jammed between the lower margin of the inlet opening 31 and the pusher roller 130 and would, therefore, be crushed or damaged due to shock so that they would not withstand the cooking pressure to which they are subsequently subjected. However, containers that rebound as aforesaid are positively deflected from the chain pockets into the turret pockets by the stripper 150 and damage to the containers is, therefore, avoided.

The lower reach of the chain 100 will normally hang in a slight catenary curve and when operating will vibrate relative to the normal pitch line between sprockets 93 and 86. As seen in Fig. 1, the stripper guide casting 155 is provided with a stabilizer shoe 165 which extends parallel to the

lower reach of the chain 100 and opposite the inlet 31 of the valve. This shoe 165 is so positioned that the spacer rollers 124 of the chain 100 will normally engage the same when the chain is on its pitch line. Consequently, as the links of the elevator chain 100 leave the drive sprocket 93, their spacer rollers 124 engage the shoe 165 and the normal vibratory action of the chain is, accordingly, minimized.

10 The maintenance of the chain on the normal pitch line thereof as the containers flow into the turret pocket is very important. It is apparent that movement of the chain outwardly from the inlet opening is limited by the shoe 165. The chain, however, tends to droop toward the opening 31 and, therefore, the chain must be maintained at a proper tenseness between the two sprockets 93 and 86. This is essential, otherwise the pusher rollers 130 are 15 likely to extend into the opening 31 and are liable to become caught on the turret or on the lower margin 38 of the inlet 31.

In order to maintain the elevator chain under 20 tension, the floating sprocket 86 is associated with a tension carriage. As hereinbefore explained, the sprocket 86 is secured to a shaft 85 having its ends rotatably mounted in bearings formed as a part of the yoke 80. These bearings have parallel faces fit into the respective guide slots 77 for sliding movement longitudinally with respect to the elevator housing 45. The yoke 80 has legs 112 extending downwardly along the longitudinal axis of the housing 45 and has a threaded boss 174 at its 25 bight. A screw 175 has one end threaded into the threaded boss 174 of the yoke and is secured thereto by a tapered pin 176. The screw 175 also extends downwardly along the longitudinal axis of the elevator housing and fits through an aperture 180 in the bottom of the casting 70 adjacent the standard 72.

A cylindrical cup 181 is formed concentric to the aperture 180 on the underside of the casting 70 and a compression spring 182 is arranged in this cup 181 and around the shank of the screw 175. The spring 182 normally extends beyond the rim 183 of the cup 181 and is compressed by an adjusting nut 184 which is threaded onto the screw 175. The nut 184 is secured in its position 30 of adjustment by a locking sleeve 185 threaded onto the end of the screw 175 to tightly engage and lock the nut 184 on the threads of the screw.

By the foregoing arrangement, the elevator chain 100 is properly tightened and any manufacturing tolerances, i. e., variations in link length or the like, are taken up by the spring 182. Consequently, as the chain travels around the sprockets 93 and 86, a pulsation of the floating sprocket is permitted.

As the chain 100 and sprockets 93 and 86 wear due to constant running, the floating sprocket 86 is free to move under the influence of the compression spring 182. The compression spring will urge the yoke, its floating bearings, and the sprocket 86 longitudinally away from the drive sprocket 93 and maintain the chain 100 under tension. When wear of the chain and sprockets becomes excessive, the nut 184 is readjusted in order to obtain the desired tension of the elevator chain, as hereinbefore explained.

While I have described a particular embodiment of the present invention, it will be understood that various changes and modifications may be made without departing from the spirit of the invention. I, therefore, do not limit myself to

the specific arrangement disclosed, but desire to avail myself of such modifications and alterations as come within the scope of the appended claim.

Having thus described my invention, what I claim as new and desire to protect by Letters Patent is:

A conveyor for lifting containers to an elevated station and discharging them from the station at equally spaced intervals, comprising a lower sprocket, an upper sprocket in vertical spaced alignment with said lower sprocket, an endless chain disposed over said sprockets and providing substantially straight ascending and descending runs, uniformly spaced flights carried by said chain and projecting away therefrom to define container-receiving pockets which open upwardly in the ascending run of the chain and substantially downwardly in the descending run, a track disposed adjacent the chain and extending along the ascending run of the chain, along the curved upper portion of the chain on said upper sprocket and part way along the descending run of the chain, stationary guide means extending around the curved upper portion of the chain and part way along the descending run, said guide means

being uniformly spaced from said track and co-operating therewith to provide a curved passageway around the upper curved end of the chain and a straight passageway adapted to retain each container in its associated inverted pocket as it moves a predetermined distance along the descending run of the chain, and a curved stripper member forming an extension of said track and extending across the path of movement of the containers at a point below the lower end of said straight passageway and at a point where the container is supported on a flight of the substantially straight descending run of said chain.
